W. M. WATTIE

MAT AND METHOD OF MAKING THE SAME

Filed May 25, 1923

Inventor
William M. Wattie
Walter H. Wakefield
Attorney.

UNITED STATES PATENT OFFICE.

WILLIAM M. WATTLE, OF WORCESTER, MASSACHUSETTS.

MAT AND METHOD OF MAKING THE SAME.

Application filed May 25, 1923. Serial No. 641,503.

This invention relates to mats and the method of their manufacture and more particularly to mats of the type disclosed in my prior Patent #910,332 granted January 19, 5 1909.

The mat disclosed in my former patent comprises fibrous cords interwoven upon a perforated framework and one advantage of this construction is that the mat has extending therethrough a number of openings 10 through which dirt may pass. However, the cords lie closely against the framework and this interferes to some extent with the cleaning of the mat and also gives a relatively hard unyielding wiping surface.

One object of my present invention is to improve upon the construction of this general type of mat by mounting the fibrous cords more loosely upon the framework than 20 has been done heretofore, this construction affording larger openings through the mat and also presenting a relatively larger and more flexible wiping surface.

It is a further object of my invention to 25 mount the cords loosely upon a framework to the end that the cords and framework may be moved relatively to each other to facilitate cleaning.

In my aforesaid patent the cords are interwoven on a metal framework by being 30 passed from one side to the other of the framework through the perforations thereof, but this mode of construction has been found to be laborious. It is another object of my 35 invention to improve upon the method of constructing the mat by avoiding interweaving with the framework so that the same may be more quickly assembled.

With these and other objects which will 40 appear as the description proceeds the invention resides in the combination and arrangement of parts hereinafter described and claimed.

In the accompanying drawings, Fig. 1 is 45 a plan view of a mat constructed according to my present invention,

Fig. 2 is a vertical longitudinal section thereof taken on line 2—2 of Fig. 1,

Fig. 3 is a diagrammatic plan view showing 50 the relation of the framework, cords, and binders,

Fig. 4 is a diagrammatic view similar to Fig. 2 but showing the behavior of the mat surface under pressure, and

55 Fig. 5 is a bottom plan view of the invention shown in Fig. 1.

In general my invention contemplates the use of a framework having perforations through which extend loops formed in cords, the connecting parts of the loops lying under the framework and the loops above the framework. If desired binders may be passed through the loops to prevent them from slipping through the framework.

Referring to the drawings it will be seen that the framework comprises longitudinal bars 10 to which are welded or otherwise secured cross bars 11, said bars being spaced so as to define openings which are preferably though not necessarily rectangular. The outermost of the bars 10 and 11 may carry an edging 12 similar to that shown in my former patent aforesaid and forming no part of the present invention.

The wiping surface of the mat is afforded 75 by a plurality of coils or loops 13 formed in cords 14 having the ends thereof secured to the frame work in a manner similar to that shown at 15 in Fig. 2. The diameter of the cord 14 is preferably such with respect to the 80 perforations in the framework that the loops fit snugly in the perforations and will be held therein against accidental displacement by friction. However, when desired, binders 16 may be passed through the loops 85 above bars 10 and substantially parallel to bars 11. In order to hold the binders in place the ends thereof may be tied around the loops 13 as indicated at 17 in Fig. 1.

This construction affords a very flexible 90 wiping surface as will be seen by referring to Fig. 4 where it will be noted that a surface to be cleaned, such as 18, will depress the loops thus lengthening the surface contact between the cord and the surface to be 95 cleaned and also preventing accidental passage of the loop through the openings in the framework because of the lengthening of the loop at the points where the pressure is applied.

In constructing my mat I preferably wrap 100 a cord into a series of coils and having secured one end of the cord to the framework I separate the coils one at a time and pass them through successive openings of the framework. The binders may thereafter be passed through the loops and secured to the loops as already described. The manner in 105 which this method may be carried out will be understood from an inspection of Figs. 2 and 5.

From the foregoing description it will be

apparent that I have provided a mat having a relatively large and flexible wiping surface which is afforded by cords held loosely to an open framework in such a way **5** as to afford large passages for dirt, etc. It will also be apparent that parallel cross members are provided some of which pass through the loops and the others of which pass over the connecting portions of the **10** loops to retain the latter in place. It will also appear that the method of manufacturing the mat described herein is more simple than that shown in my former patent and greatly lessens the labor of manufacture of **15** my herein described mat.

Having described my invention it will be apparent that changes and modifications can be made therein by those skilled in the art and I do not wish to be limited to the **20** details set forth herein, but what I claim is:

1. In a mat, a metallic framework having openings therein, and cords each formed with loops, successive loops passing through adjacent openings in the framework and ex-

tending on one side of the framework, the **25** portions of the cords between the loops lying on the opposite side of the framework.

2. In a mat, a framework having openings therein, and a flexible cord formed in a **30** series of loops, the loops passing through openings of the framework to present spaced wiping surfaces, and each opening containing but one loop of the series.

3. In a mat, a framework having openings therein, cords having formed therein **35** loops extending from one side of the framework through said openings to the other side of said framework, and retaining members passing through the loops.

4. The method of forming mats which **40** consists in providing a framework having perforations therein, coiling a cord, separating the coils to form separate loops and passing the loops through the perforations of the framework.

In testimony whereof I have hereunto affixed my signature.

WILLIAM M. WATTIE.
